UNITED STATES PATENT OFFICE

JULIUS J. BLUMENTHAL, OF NEW YORK, N. Y., ASSIGNOR TO LIGHTING APPLIANCE COMPANY, INC., OF NEW YORK, N. Y.

DESIGN FOR A LIGHTING FIXTURE OR ARTICLE OF SIMILAR NATURE

Application filed August 8, 1930. Serial No. 36,602. Term of patent 8½ years.

To all whom it may concern:

Be it known that I, JULIUS J. BLUMENTHAL, a citizen of the United States, residing in New York, in the county of Kings and State of New York, have invented a new, original, and ornamental Design for a Lighting Fixture, or Article of Similar Nature, of which the following is a specification, reference being had to the accompanying drawings, forming a part thereof.

Fig. 1 is a perspective view of a lighting fixture showing my new design.

Fig. 2 is a diagrammatic cross sectional view of half of the fixture showing the arrangement of the panels.

The view from the sides and rear is similar to that shown in Fig. 1 of the drawing, the fixture being symmetrical.

I claim:

The ornamental design for a lighting fixture, or article of similar nature, as shown and described.

In testimony whereof I affix my signature.

JULIUS J. BLUMENTHAL.
